United States Patent Office.

NATHAN DEWEY AND GEORGE W. FOSDICK, OF DOWAGIAC, MICHIGAN.

Letters Patent No. 77,595, dated May 5, 1868.

IMPROVEMENT IN WATER-WHEELS.

The Schedule referred to in these Letters Patent and making part of the same.

TO ALL WHOM IT MAY CONCERN:

Be it known that we, NATHAN DEWEY and GEORGE W. FOSDICK, of Dowagiac, in the county of Cass, and in the State of Michigan, have invented a new and useful Improvement in Water-Wheels; and we do hereby declare that the following is a full, clear, and exact description thereof, reference being had to the accompanying drawing, and to the letters of reference marked thereon:

In the annexed drawing, making part of this specification, A represents a horizontal water-wheel, which is made as follows: We use two rim-wheels, B and C, which are cast of sufficient depth, and the one, B, being made as much less in diameter than the other as it is desired that the width of the buckets should be. These wheels, B and C, are concentric, and have a common axle or shaft, E, which is connected to the inner wheel by means of the arms F F. G and D represent the buckets of this water-wheel A, and in this instance are eight in number of each kind. The buckets G are intended to receive the direct action of the water, and are made nearly L-shaped, with one ring standing vertically and the other horizontally, or nearly so, the water being received on the angular side, and exerting its percussive power against the vertical side mainly. D represents the other series of buckets, which lie immediately beneath the buckets G, in an inclined position, and receive the force of the reaction and weight of the water. The upper edges e e of these buckets are flush with the upper edges of the rim-wheels. The buckets, as they incline downward, have a suitable torsion given them, so that the outer corner of the lower edge reaches down to the lower edge of the outer rim-wheel C, while the inner corner of this edge lies against the inner rim-wheel, about two-thirds of its way toward its lower edge. By this torsion of the buckets the water is discharged at or near their lower outer corners, and near the periphery of the wheel. H represents a scroll-chute, which is made in a spiral tapering form, with two sides and top, but without bottom, and is placed immediately over the buckets of the wheel A. The centre of this scroll is composed of a disk or plate, I, which is made just large enough to lie upon the inner rim-wheel B, covering its internal surface.

The scroll is provided with a flange, J, on its outer lower edge, which rests at suitable points upon standards for supporting the scroll, and securing it firmly in its place. This scroll is made of such size and taper that it will supply, as nearly as possible, the exact amount of water which the wheel will receive at each bucket.

Back water does not obstruct the action of this wheel. In setting the wheel, its top is on a level with the surface of the water in the tail-race. We thus obtain a fall over other wheels equal to the depth of our wheel.

This wheel may be set in the bottom of the flume, and a series of gates, to correspond with the number of buckets, used for regulating and cutting off the supply of water.

Having thus fully described our invention, what we claim as new, and desire to secure by Letters Patent, is—

The wheel A, composed of the rims B C and their buckets D and G, the buckets D being curved and inclined from the upper portion of the inner rim to the lower portion of the outer rim, all constructed and operating substantially as specified.

In testimony that we claim the foregoing, we have hereunto set our hands, this 18th day of November, 1867.

NATHAN DEWEY,
GEO. W. FOSDICK.
